UNITED STATES PATENT OFFICE.

CEYLON R. CADY, OF DETROIT, MICHIGAN.

METHOD OF RESTORING MOLDING-SAND.

1,205,323.

Specification of Letters Patent. Patented Nov. 21, 1916.

Application filed January 24, 1916. Serial No. 73,799.

To all whom it may concern:

Be it known that I, CEYLON R. CADY, a citizen of the United States of America, residing at Detroit, in the county of Wayne and State of Michigan, have invented certain new and useful Improvements in Methods of Restoring Molding-Sand, of which the following is a specification, reference being had therein to the accompanying drawings.

It is the object of the invention to obtain a treatment for molding sand by which the hot sand from one molding operation is quickly cooled and re-tempered to be available for another operation.

In the present state of the art molding sand is usually used but once in a day, and the re-tempering process is one requiring considerable time for cooling and distributing the proper amount of moisture. Thus in large plants it is necessary to keep on hand a relatively large quantity of the sand which is not in use. This is objectionable, both on account of the cost and particularly by reason of the space required for the storing of the unused sand. With the present invention the sand may be so quickly cooled and re-tempered that it is available for practically continuous use, thereby reducing both the quantity required and the space for its storage.

In the drawings is shown a diagrammatic vertical section through a form of apparatus adapted for the carrying out of my improved process.

The primary step in my improved process is the abstraction of the heat from sand which is just removed from the molding flasks. This is accomplished by passing the sand through a cooling apparatus, and preferably by subjecting it to contact with a cooling air current. It is, however, essential to guard against the blowing away of the dry dust which forms the binder for the particles of sand, and I therefore combine the cooling treatment with a moistening treatment. Furthermore, this moistening facilitates the cooling by dissipating a portion of the heat through the evaporation of the water and also effects the tempering of the sand or the moistening of the binder to an extent which renders it adhesive.

The apparatus as specifically shown comprises a vertically-extending casing A, into the upper end of which the hot sand is introduced through a conduit B from an elevator

C. At the entrance end of this casing is an oscillating screen D, which distributes the sand and permits it to fall in separate streams, and at various intermediate points in the casing are similar oscillating screens D', D'' and D''. Connected to the lower end of the casing is a conduit E, through which a blast of cold air is introduced from any suitable source, the air passing upward through the series of screens and between the falling streams of sand.

F are pipes for the introduction of moisture, preferably water, which is sprayed by the series of nozzles G G', etc., and is introduced into the several compartments intermediate the screens.

With the apparatus as described, the hot dry sand which is raised by the elevator C is passed through the casing A in opposition to the air current, which, coming into intimate contact with the separate grains of sand, quickly abstracts the heat. At the same time the water spray will sufficiently moisten the binder adhering to the particles of sand to prevent the carrying away of the same by the air current. Also introducing this moisture at a series of points avoids on the one hand the washing off of the binder, and on the other hand continuously renews the moisture which is abstracted by evaporation. Thus when the sand reaches the bottom of the casing A it is thoroughly cooled and may if necessary then be introduced into any suitable mixing and tempering apparatus, such as indicated at H.

What I claim as my invention is:

1. The process of restoring molding sand, comprising the feeding of the hot sand through a conduit in one direction, the passing of a current of air through said conduit in the opposite direction, and the introduction of moisture to the sand while under air treatment.

2. The process of restoring molding sand, comprising the screening of the hot sand to separate the particles thereof, the subsequent passing of a current of air in opposition to the screened sand and the introduction of moisture.

3. The process of restoring molding sand, comprising the passing of the hot sand through a conduit, screening the sand at a series of points in said conduit to separate the same into fine streams, the passage of a cooling current of air through said conduit

in opposition and the introduction of moisture.

4. The process of restoring molding sand, comprising the dropping of the hot sand through a vertical conduit, screening of the sand at a plurality of points in said conduit to separate the same into fine streams, the passing of a cooling air current through said conduit in opposition to the sand and 10 the introduction of moisture at a series of points.

5. The process of cooling molding sand consisting in causing the sand to fall within a confined area and in forcing a current 15 of air upwardly through said area.

6. The process of restoring molding sand consisting in causing the sand to fall within a confined area, forcing a current of air upwardly through said area, and in spraying the falling sand.

7. The process of cooling molding sand consisting in causing the sand to fall within a confined area, forcing a current of air upward through said area and distributing the falling sand substantially throughout 25 the entire confined area to secure a maximum surface contact of air and sand.

8. The process of restoring sand consisting in alternately screening and moistening the same within a confined area and in forcing 30 a current of air through said area.

9. The process of restoring molding sand, comprising the feeding of the hot sand through a conduit, the passage of an air current longitudinally through said conduit, 35 and the application of moisture to the sand allowing its passage through said conduit.

In testimony whereof I affix my signature.

CEYLON R. CADY.
